DESIGN FOR A DRESS

Marie V. Mascitelli, New York, N. Y.

Application April 14, 1939, Serial No. 84,286

Term of patent 3½ years

To all whom it may concern:

Be it known that I, Marie V. Mascitelli, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design, and

Fig. 2 is the rear view thereof.

I claim:

The ornamental design for a dress, substantially as shown.

MARIE V. MASCITELLI.
